ELECTRIC SWITCH

Olan Richardson, Hampton, Ga., assignor to
 Southern States Equipment Corporation, a corporation of Georgia

Application February 19, 1953, Serial No. 337,781

16 Claims. (Cl. 200—48)

1

This invention relates to electric switches and more particularly to operating mechanisms for high voltage switches of the air break or disconnect type.

In switches of the type wherein a switch blade is movable about a pivotal mounting relative to a fixed contact and wherein the blade is rotatable about its longitudinal axis to establish high pressure contact with the spaced jaws of the cooperating fixed contact, an operating mechanism is required which is capable of applying the proper forces to the switch throughout the switch opening and closing strokes. Since the cooperating parts of the switch operating mechanism must change their relative positions during an operating stroke and since the paths of travel of the various elements of the switch and its operating mechanism do not inherently produce the desired switch movement, it has been the practice to utilize mechanisms which are provided with lost motion connections or which incorporate yieldable elements or which produce some undesired switch movements in order to avoid a tendency of the parts to become jammed when in certain positions. For example, a switch which utilizes yieldable elements or lost motion connections is disclosed in Patent 2,520,036 Gussow and Curtis granted August 22, 1950, and assigned to the assignee of this invention.

A principal object of this invention is to provide an improved operating mechanism by which positive and smooth operating movement may be obtained in switches of the type in which a movable blade is rotatable about its longitudinal axis and movable about a pivotal mounting in order to open and close the controlled circuit.

Another object of this invention is the provision of a switch operating mechanism by which a uniform switch movement is obtained which is entirely independent of the effects of gravity or other external forces.

A further object of this invention is to provide a switch operating mechanism which is readily adjustable so as precisely to predetermine the relative positions of the movable and fixed contacts of the switch and so as to render the switch easily and smoothly operable.

A still further object of this invention is the provision of an improved switch operating mechanism which is relatively free of friction and which is constructed with ample leverage to afford easy and positive operation of the switch under all service conditions likely to be encountered.

The invention in one form as applied to a high voltage electric switch having a blade which

2

is rotatable about its longitudinal axis and which is pivotally mounted for swinging movement utilizes cam means interconnected with a universal joint to establish a driving relationship between the switch blade and a driving crank movable in a plane which is disposed transverse to the plane of swinging movement of the switch blade.

For a better understanding of the invention reference may be had to the following description taken in conjunction with the accompanying drawings in which Fig. 1 is a plan view of a switch embodying the invention; Fig. 2 is a side elevation of the switch shown in Fig. 1; Fig. 3 is a partial end view of the switch shown in Fig. 1 with the blade represented as being in the closed position; Fig. 4 is a view similar to Fig. 3 with the switch parts shown just prior to the final contact engaging movement or just subsequent to the initial contact disengaging movement; Fig. 5 is a partial side view of the switch operating mechanism showing the parts in the fully opened position; Fig. 6 is a partial section view on the line 6—6 of Fig. 2 showing the parts when the switch is fully closed; Fig. 7 is a cross-section view of the driving and driven members of the switch operating mechanism which are constructed according to the invention; Fig. 8 is a plan view partially in section along the line 8—8 of Fig. 2; Fig. 9 is a side view partially in section of the structure represented in Fig. 8 together with certain parts associated therewith; Fig. 10 is a view similar to Fig. 7 and represents a modification of the invention; Fig. 11 is a view similar to Figs. 7 and 10 and represents another modification of the invention; Figs. 12 and 13 are side and end views respectively of structure similar to that shown in Figs. 7, 10 and 11 and which represents still another modification of the invention; Fig. 14 represents a still further modification of the invention; and Fig. 15 is a schematic view of a mechanism such as is shown in Fig. 14 but with a different relationship to the universal joint.

As is indicated in Figs. 1 and 2, the switch parts are mounted on a base member 1 which may be in the form of a metallic channel member. Affixed to the left-hand end of the base element 1 is an insulator stack 2 and a similar insulator stack 3 is securely fixed in position on the right-hand end of the base member 1. A switch terminal 4 is affixed to the top of the fixed insulator stack 2 and is in electrical contact with the fixed jaw contact comprising jaw elements 5 and 6. The other terminal of the switch is indicated by

the numeral 7 and as is clearly shown in Figs. 1 and 2 is formed integrally with a yoke element 8 which is secured by bolts 9 atop the fixed insulator 3. As is shown in Figs. 1 and 2 the left-hand end of the yoke element 8 is provided with a pair of prongs 10 and 11 which terminate in a downwardly extending portion 12 which is interconnected with a rotatable insulator 13 by a journal connection schematically represented at 14 in Fig. 2. Rotatable insulator 13 is provided with a journal mounting at the lower extremity of the metallic element 15 as schematically represented at 16. Secured to the metallic extension 15 is an operating crank 16a to which force is applied to rotate the insulator stack 13. In view of the above description it will be obvious that the yoke element 8, having its right-hand end securely affixed by the bolts 9 to the fixed insulator 3, serves as a bearing for the upper end of the insulator stack 13 and as such lends support thereto. The yoke element 8 also serves as a mounting means for the jaw contacts 17 and 18 which are secured to the yoke element 8 by means of the bolts 19. In addition to acting as a bearing support for the insulator stack 13 and as support means for the jaw contacts 17 and 18 the yoke element 8 also serves to support the pivot 20 for the hinge element 21 of the switch blade generally designated by the numeral 22. As is represented in Figs. 1 and 2 the switch blade 22 comprises a tubular element 23 to the left-hand end of which is affixed a contact tip 24 and to an intermediate portion thereof is affixed a contact tip 25. Affixed to the right-hand end of the blade 23 is a tubular extension 26 which is rotatable within the hinge element 21 and which is provided at its right-hand extremity with an element 27 which is provided with a pivot 28. Thus with the parts in the position shown in Figs. 1, 2, and 3 the contact tips 24 and 25 are in engagement with the jaw contacts 5 and 6 and 17 and 18 respectively and the circuit is complete through the switch from terminal 4, contacts 5 and 6, contact tip 24, tubular element 23, contact tip 25, jaw contacts 17 and 18, yoke element 8, 45 and terminal 7.

High pressure contact is achieved in known manner by the blade tips 24 and 25 when disposed horizontally so as to stress the jaw contacts 5 and 6 and 17 and 18 as represented in Fig. 3. When it is desired to open the switch, the blade portion 23 and parts associated therewith are rotated about the longitudinal axis of the switch blade to a position wherein the contact tips 24 and 25 do not engage the jaw contacts 5 and 6 and 17 and 18 as represented in Fig. 4. Thereafter the circuit opening operation is completed by causing the switch blade to swing about the hinged pivot 20 to the position represented in Fig. 5. This complex motion of the switch blade 22 is imparted thereto by means of the crank 29 which is rotated by means of the crank 16 acting through rotatable insulator 13 and which is interrelated with the blade 22 through a linkage and cam mechanism constructed according to this invention. As already explained, the crank 29 is rotatable with the insulator stack 13, this crank 29 being affixed thereto at the collar 13'. As is shown in Fig. 9, the downwardly extending portion 12 of the yoke member 8 is provided with a neck portion 30 to which is affixed a washer 31 by means of a nut 32, these parts forming a bearing connection through the opening 33 formed in the crank element 29.

According to this invention the crank 29 is 75

provided with a suitable driving member which may constitute the rounded end portion 33 of the crank or which may be in the form of a sleeve 33a as indicated in Fig. 7. Disposed within the end portion 33 is a driven element 34 which is provided at its upper end with a follower pin 35 and with a transversely extended follower pin 36 at its lower end. From Figs. 6 and 7 it will be understood that the upper end of the driving sleeve 33a is provided with a pair of diametrically disposed recesses 37 and that the lower end of this sleeve is provided with a pair of diametrically disposed projections 38, these recesses 37 and projections 38 being cooperable with the pins 35 and 36 respectively. The driving element 34 is interconnected with a link member 39 by a universal joint comprising the pins 40 and 35 and the element 41. Link 39 is interconnected with the extension 27 of the blade 22 by means of the pivot 20. As is best shown in Fig. 6 the end portion 33 of crank 29 is provided with a pair of recesses 42 which coincide with recesses 37 in sleeve 33a and projections 43 are arranged on the lower portion of element 33 to coincide with projections 38 on sleeve 33a.

Figs. 6 and 8 respectively represent the link 39 and the crank 29 in a solid line position designated by the letter A and in addition represent these parts in a dotted line position represented by the letter B. Position A corresponds to the fully closed position of the blade 22. Position B corresponds to the position of the parts during a switch operating movement after the switch blade has been rotated about its longitudinal axis but before any appreciable swinging movement of the blade about the pivot 20 has occurred during an opening operation. It will be understood that the crank 29 and its driving element 33-33a move in an arcuate path in a horizontal plane. It will furthermore be understood that the lower extremity of the link 39 and parts associated therewith swing in a down-and-up arcuate path during the cone-like movement of link 39. Thus it will be understood that as the link 39 swings from the position designated by the letter A to that designated by the letter B the pin 40 will move downwardly to a position midway between positions A and B and thereafter will move upwardly to the position B so as to describe an arcuate path which when viewed in plan as represented in Fig. 8 is arcuate due to the arc described by the driving element 33 of the crank 29 when moved about its center position. Since the driven member 34 and the link 39 and parts associated therewith do not rotate about their own axes during travel between positions A and B and since the driving element 33-33a does change its angular position relative to the center of rotation of the crank 29, there is necessarily a relative rotary movement between the driving element 33-33a and the driven element 34. Since the driving element 33 during its movement in an arcuate path does not move in the vertical direction and since the link 39 and parts associated therewith must move vertically, I provide suitable cam means for accommodating this divergence in the vertical movement of these two parts while maintaining a positive relationship therebetween. Thus in accordance with a feature of this invention the recesses 37 in the driving element 33a and recesses 42 in crank 33 receive the pin 35 during the time when the parts are moving from position A to position B. Similarly the lower pin 36 is caused to ride over the projections 38 in the sleeve 33a and the projections

43 formed on the lower surface of the driving element 33. Thus the ends of elements 33 and 33a and pins 35 and 36 constitute cam means. After the parts move through the mid-position between positions A and B the pin 35 begins to ride out of the cam surfaces 37 and 42 and continues about the upper end surfaces of the driving element 33—33a and by the same token the pin 36 rides over the projecting portions 38 and 43 and continues to move about the lower end portion of the driving element 33—33a.

As is understood in the art, continued movement of the operating crank 29 from the position designated by the letter B to the position designated by the letter C, causes the switch blade 22 to swing about the pivot 20 from the position indicated in Figs. 1 and 2 to that represented by Fig. 5.

The arrangement disclosed in Fig. 10 represents a modification of that disclosed in Figs. 5, 6, and 7. The arrangement of Fig. 10 constitutes what I presently consider to be a preferred embodiment of the invention.

In Fig. 10 the driven element 34 is provided with a wide groove 44 for minimizing frictional effects between that element and the sleeve 33a and in addition bearing sleeves 45 are provided to reduce the frictional losses between these parts. Bearings 45 could be of metallic material impregnated with a lubricating substance. For further reducing frictional effects, the pins 35 and 36 may be respectively provided with rollers 46 and 47 which, if desired, could be mounted on roller bearings. As is indicated in Fig. 10 the portion 33 of the crank 29 is formed of a split construction with projecting tabs 48 and a bolt 49 arranged to form a gripping relationship about the driving sleeve 33a. If desired, the driving element 33a may be secured in position within the element 33 by means of a tapered pin 50 so as to maintain the parts securely in position. One possible advantage of the arrangement shown in Fig. 10 is that the driven element 34 and the driving element 33 and parts associated therewith may be constructed as a subassembly and furthermore these parts are readily adjustable relative to the driving element 33 before the pin 50 is inserted in position. As in Figs. 3, 6, and 7 the upper and lower ends of sleeve 33a are respectively provided with surfaces 37a and 38a. Unlike Figs. 6 and 7, Fig. 10 does not require cam surfaces in element 33 since sleeve 33a is long enough to prevent rollers 46 and 47 from engaging the ends of member 33.

The modification shown in Fig. 11 utilizes a driving element 33 in the form of an opening in crank 29 and the driven element 34 is provided with a transverse pin 51 on the ends of which roller elements 52 are mounted. A collar element 53 is disposed about the upper end of the driven element 34 and may be held in position by the gripping action of the upper end of the element 33 due to the tightening of the nut 54 which cooperates with the bolt 55 and the projecting tabs 56. Similarly a collar 53a is disposed about the lower portion of the element 34 and is secured within the driving element 33 by means of the nut 54a, the bolt 55a and the projecting tabs 56a. If desired, the collars 53 and 53a may be secured in position by means of the tapered pins 50 and 50a. The collar 53 is provided with diametrically opposite projections 37b and the collar 53a is provided with diametrically opposite recessed portions 38b. Thus swinging movement of the crank arm 29 causes the rollers 52 to ride

along a path defined by cam surfaces 37b and 38b.

In the arrangement shown in Figs. 12 and 13 the driven element 34 is provided with a groove, the irregular upper surface of which is indicated at 37c and the irregular lower surface of which is indicated at 38c and projecting pins which are laterally adjustable and which are designated by the numeral 57 are arranged with the inner ends thereof disposed within the groove or grooves in the element 34. If desired, ball bearings 58 may be provided. Relative motion in a vertical direction between the parts 33 and 34 is accommodated by the irregular portion 37c—38c of the groove formed in the driven element 34.

In Fig. 14 the crank 29 is provided with an opening in which the driving element 59 is affixed by clamping action of tabs 60, bolt 61 and nut 62. Pin 63 can be used if desired to maintain the element 59 securely in position. Disposed within the driving element 59 is a transverse pin 64 provided with rollers 65. An inverted cup-shaped driven member 66 is provided with diametrically opposite recesses 37d. A short sleeve 67 having an internal flange 68 is secured by threads 69 and set screw 70 to the element 66. Projections 38d are formed in the flange 68 to correspond to the recesses 37d in element 66. This modification has the advantage of affording protection against precipitation.

The arrangement shown in Fig. 15 is like that of Fig. 14 except that in Fig. 15 the universal joint is interposed between the driving crank 29 and the cam means comprising elements 64, 65, 66, and 67. Also the crank 39 forms a unitary connecting link between the cam means and the pin 20. The universal joint comprises the small end portion 73 of crank 29, the pin 71 and the element 72. Element 66 is formed integrally with crank 39.

From the above description it will be understood that according to the invention, I have provided an improved switch operating mechanism wherein positive control of the switch is maintained by the mechanism at all times. Furthermore it will be understood that I achieve this result with a mechanism which does not have a tendency to jam or to ride through so-called "hard spots." It will also be appreciated that gravity or other external forces cannot cause movement of the switch blade relative to the operating mechanism.

While I have shown and described several embodiments of the invention, I do not wish to be limited thereto and intend in the appended claims to cover all such changes and modifications as fall within the true spirit and scope of the invention.

What I claim as new and desire to secure by Letters Patent of the United States is:

1. An electric switch comprising a fixed contact, a switch blade rotatable about its longitudinal axis and pivotally mounted for swinging movement relative to said fixed contact, a crank movable in a plane transversely disposed relative to the plane of swinging movement of said blade, a link having one end thereof pivotally connected with said blade, and means including cam means interconnected between said crank and the other end of said link for establishing a positive operative relationship therebetween.

2. An electric switch comprising a fixed contact, a switch blade rotatable about its longitudinal axis and pivotally mounted for swinging movement relative to said fixed contact, a crank movable in a plane transversely disposed relative

to the plane of swinging movement of said blade, a link having one end thereof pivotally connected with said blade, and means including cam means interconnected between said crank and the other end of said link for establishing a positive operative relationship therebetween, said cam means including a driven member operably related with said link and a driving member operably related with said crank, one of said members having a cam surface engaging a corresponding surface of the other of said members so as to impart controlled operating movement to said switch blade in response to operating movement of said crank.

3. An electric switch comprising a fixed contact, a switch blade rotatable about its longitudinal axis and pivotally mounted for swinging movement relative to said fixed contact, a crank movable in a plane transversely disposed relative to the plane of swinging movement of said blade, a link having one end thereof pivotally connected with said blade, and means including cam means interconnected between said crank and the other end of said link for establishing a positive operative relationship therebetween, said cam means including a driving member operably related with said crank and a cooperating driven member operably related with said link, said members being relatively movable in a direction transverse to the plane in which said crank is movable during a portion of an operating stroke.

4. An electric switch comprising a fixed contact, a switch blade rotatable about its longitudinal axis and pivotally mounted for swinging movement relative to said fixed contact, a crank movable in a plane transversely disposed relative to the plane of swinging movement of said blade, a link having one end thereof pivotally connected with said blade, and means including cam means interconnected between said crank and the other end of said link for establishing a positive operative relationship therebetween, said cam means including a driving member operably related with said crank and a telescopically related driven member operably related with said link, said members being coaxially disposed at all times and having engaging surfaces arranged to impart relative movement thereto in an axial direction during at least a portion of the rotary movement of said blade in response to rotary displacement of said driving member relative to said driven member.

5. An electric switch comprising a fixed contact, a switch blade rotatable about its longitudinal axis and pivotally mounted for swinging movement relative to said fixed contact, a crank movable in a plane transversely disposed relative to the plane of swinging movement of said blade, a link having one end thereof pivotally connected with said blade, and means including cam means interconnected between said crank and the other end of said link for establishing a positive operative relationship therebetween, said cam means including a driven member operably related with said link and a driving member operably related with said crank, one of said members having a cam surface engaging a corresponding surface of the other of said members so as to impart controlled operating movement to said switch blade in response to operating movement of said crank and said members being adjustable relative to said crank in a direction transverse to the plane in which said crank is movable.

6. An electric switch comprising a fixed contact, a switch blade rotatable about its longitudinal axis and pivotally mounted for swinging

movement relative to said fixed contact, a crank movable in a plane transversely disposed relative to the plane of swinging movement of said blade, a link having one end thereof pivotally connected with said blade, a driven member connected with the other end of said link by a universal joint, and a driving member operably related with said crank, the cooperating surfaces of said members constituting cam means for establishing a positive operating relationship between said driving and said driven members during at least a substantial portion of an operating stroke of said blade and in a direction normal to the plane in which said crank is movable.

15 5. An electric switch comprising a fixed contact, a switch blade rotatable about its longitudinal axis and pivotally mounted for swinging movement relative to said fixed contact, a crank movable in a plane transversely disposed relative to the plane of swinging movement of said blade, a driven member operably related with said blade, and a driving member connected with said crank by a universal joint, said driving and said driven members having cooperating cam surfaces configured to establish a positive operative relationship therebetween.

20 6. An electric switch comprising a fixed contact, a switch blade rotatable about its longitudinal axis and pivotally mounted intermediate its ends for swinging movement relative to said fixed contact, a crank movable in an arcuate path in a plane transversely disposed relative to the plane of swinging movement of said blade, a link having one end thereof pivotally connected with one end of said blade, a driven member connected with the other end of said link by a universal joint, and a driving member movable with said crank and telescopically related with said driven member, the engaging surfaces of said members constituting cam means for imparting relative movement to said members in a direction axially thereof in response to operating movement of said crank and rotary motion of said driving member relative to said driven member.

30 7. An electric switch comprising a fixed contact, a switch blade rotatable about its longitudinal axis and pivotally mounted intermediate its ends for swinging movement relative to said fixed contact, a crank movable in a plane transversely disposed relative to the plane of swinging movement of said blade, the swing end of said crank being formed with an opening therein, a link having one end thereof pivotally connected with one end of said blade, a driven member connected with the other end of said link by a universal joint and disposed in said opening in said crank, said driven member and said crank being provided with engaging surfaces configured to impart motion to said driven member in a direction substantially normal to the plane in which said crank moves during at least a portion of the operating movement of said switch, and means for operating said crank.

35 8. An arrangement according to claim 9 wherein the opening in said crank extends in a direction generally normal to the plane in which said crank is movable, wherein projecting means extends inwardly from a wall defining said opening, and wherein the driven member comprises an element having an irregular groove formed in its surface for receiving said projecting means so that rotary movement of the swing end of said crank relative to said driven member results in relative movement therebetween in a direction generally normal to the plane in which said crank

11. An arrangement according to claim 9 wherein the opening in said crank extends in a direction generally normal to the plane in which said crank is movable, wherein projecting means extends inwardly from a wall defining said opening, wherein the driven member comprises an element having an irregular groove formed in its surface for receiving said projecting means so that rotary movement of the swing end of said crank defining said opening relative to said driven member results in relative movement therebetween in a direction generally normal to the plane in which said crank is movable, and wherein bearing means is disposed within said opening about said element.

12. An electric switch comprising a fixed contact, a switch blade rotatable about its longitudinal axis and pivotally mounted for swinging movement relative to said fixed contact, a crank movable in a plane transversely disposed relative to the plane of swinging movement of said blade, the swing end of said crank being formed with an opening therein, a link having one end thereof pivotally connected with said blade, a cup-shaped element having an irregular path along an inside wall thereof and connected with the other end of said link by a universal joint, a pin disposed in the opening in said crank and having a transversely disposed follower element for riding in the path in the wall of said cup-shaped element thereby to accommodate relative movement therebetween in a direction transverse to the plane of movement of said crank in response to movement of said crank.

13. An electric switch comprising a fixed contact, a switch blade rotatable about its longitudinal axis and pivotally mounted for swinging movement relative to said fixed contact, a crank movable in a plane transversely disposed relative to the plane of swinging movement of said blade, a link having one end thereof pivotally connected with said blade, a driven member connected with the other end of said link by a universal joint, and a driving member operably related with said crank, the cooperating surfaces of said members being configured so that movement of said crank results in controlled relative movement of said members during at least a portion of an operating stroke of said blade and in a direction normal to the plane in which said crank is movable, said driving member comprising a sleeve supported by said crank and having irregularly shaped end surfaces and said driven member comprising an element disposed within said sleeve and provided at each end thereof with follower means disposed to cooperate with said end surfaces of said sleeve.

14. An electric switch comprising a fixed contact, a switch blade rotatable about its longitudinal axis and pivotally mounted for swinging movement relative to said fixed contact, a crank movable in a plane transversely disposed relative to the plane of swinging movement of said blade, a link having one end thereof pivotally connected with said blade, a driven member connected with the other end of said link by a universal joint, and a driving member operably related with said crank, the cooperating surfaces of said members being configured so that movement of said crank results in controlled relative movement of said members during at least a portion of an operating stroke of said blade and in a direction normal to the plane

in which said crank is movable, said driving member comprising a sleeve movable with said crank and having irregularly shaped end portions and said driven member comprising an element disposed within said sleeve and provided at each end with roller means arranged to cooperate with said end portions of said sleeve, and said crank being provided with holding means for adjustably positioning said sleeve and said element.

15. An electric switch comprising a fixed contact, a switch blade rotatable about its longitudinal axis and pivotally mounted for swinging movement relative to said fixed contact, a crank movable in a plane transversely disposed relative to the plane of swinging movement of said blade, a link having one end thereof pivotally connected with said blade, a driven member connected with the other end of said link by a universal joint, a driving member operably related with said crank, the cooperating surfaces of said members being configured so that movement of said crank results in controlled relative movement of said members during at least a portion of an operating stroke of said blade and in a direction normal to the plane in which said crank is movable, said driving member comprising a sleeve movable with and supported by said crank and formed with irregularly shaped end surfaces and said driven member comprising an element disposed within said sleeve and provided at each end with roller means disposed to engage and follow said end surfaces of said sleeve in response to relative rotary motion of said sleeve and said element, and bearing means interposed between the inner surface of said sleeve and said element.

16. An electric switch comprising a fixed contact, a switch blade rotatable about its longitudinal axis and pivotally mounted intermediate its ends for swinging movement relative to said fixed contact, a crank movable in an arcuate path in a plane transversely disposed relative to the plane of swinging movement of said blade, a link having one end thereof pivotally connected with one end of said blade, a driven member connected with the other end of said link by a universal joint, a driving member movable with said crank and telescopically related with said driven member, the engaging surfaces of said members being configured to impart relative movement to said members in a direction axially thereof in response to operating movement of said crank and rotary motion of said driving member relative to said driven member, said driving member comprising an opening in said crank extending in a direction transverse to the plane in which said crank is movable and having an irregular path disposed along the wall of said opening and said driven member comprising an element disposed in said opening and provided with follower means secured thereto and disposed in said path so that relative rotary motion between said crank and said element results in relative movement therebetween in a direction normal to the plane in which said crank is movable.
